POWER UNIT CASING FOR AN ELECTRIC MIXER OR THE LIKE

Earl Rutan, Pound Ridge, N. Y., assignor to Loral Electronics Corp., Bronx, N. Y., a corporation of New York

Application September 17, 1956, Serial No. 42,964

Term of patent 14 years

(Cl. D89—1)

Fig. 1

Fig. 1

Fig. 2

Fig.3

Fig.4

Figure 1 is a view in perspective of a power unit casing for an electric mixer or the like showing my new design;

Figure 2 is a second view in perspective showing the longitudinal side disposed opposite that seen on Figure 1;

Figure 3 is a plan view thereof; and

Figure 4 is a perspective view showing the side disposed opposite that seen on Figure 2.

I claim:

The ornamental design for a power unit casing for an electric mixer or the like, as shown.
